DIABOLO GAME TOP

Mathew T. Laurens, Binghamton, and Stanley J. Anderson, Conklin, N. Y.

Application June 20, 1951, Serial No. 232,634

1 Claim. (Cl. 46—60)

1
The present invention relates to a diabolo and it consists in the combinations, constructions and arrangements of parts herein described and claimed.

Generally there is provided a balancing type toy which may be used by one or more persons. The toy is a double-conical frustum with the lesser diameter at the center. The toy is molded of plastic or may be formed of other suitable material and is cored from the center outwardly for lightness and economy, the outer ends being scalloped. The ends of the toy are closed by means of end plates which are cemented to the body and each end plate has a rotary fan-type disc pivotally attached by means of a pin which is set into a radial ball-type bearing to minimize friction. The fan disc is spaced from the end plate by a steel washer and the disc contains four propeller blades which will cause the disc to rotate about the pivot pin and air slots in the disc will cause a siren-type noise as the fan rotates over the air holes in the end plate. The scalloped edges of the toy prevent damage to the fan whenever it falls, the edges, however, still permitting the fan to receive sufficient air therethrough to rotate. Holes are provided in the body of the toy to permit a through passage of air. The users of the device each are supplied with a pair of sticks which are interconnected by a "chalk line string" and the device is manipulated by balancing the same and rotating the same upon the string and after such rotation reaches a given point the toy may be thrown from one person to another utilizing the sticks and string only for throwing and receiving the toy.

It is accordingly an object of the invention to provide a device of the character set forth which is simple in construction, inexpensive to manufacture and yet effective and efficient in use.

Another object of the invention is the provision, in a device of the character set forth, of novel means for balancing and rotating the same.

Still another object of the invention is the provision, in a device of the character set forth, of novel means for producing sounds therein.

Other and further objects of the invention will become apparent from a reading of the following specification taken in conjunction with the drawing, in which:

Figure 1 is a perspective view of an embodiment of the invention illustrating the manner of rotating and balancing the same.

Figure 2 is an enlarged sectional view, partly in elevation, taken along line 2—2 of Figure 1, 55

2
Figure 3 is a fragmentary exploded perspective view illustrating certain details of construction in the device illustrated in Figure 2.

Figure 4 is a vertical longitudinal sectional view of a modified form the invention may assume, and

Figure 5 is an end elevational view of the device illustrated in Figure 4.

Referring more particularly to the drawing, there is shown therein, in Figures 1 to 3, inclusive, a toy of the character above set forth having a body in the form of a double-conical frustum with the lesser diameter at the center, as indicated at 10, the conical portions of the body being indicated at 11.

The outer ends of each of the cones 11 are scalloped, as indicated at 12 and immediately inwardly of the outer edges in each case there is affixed by cementing or the like a disc shaped end plate 13 having a plurality of radially extending spaced slots 14 formed therein.

The center portion of the plate 13 is provided with an integrally formed hub 15 in which is mounted a radial ball bearing 16 which bears against the hub 17 of a fan disc 18 which is mounted upon the hub 17 by means of a pin 19. The fan disc 18 is provided with a plurality of propeller blades 20 and each of the hollow cones 11 is provided with a series of spaced circumferentially extending openings 21.

In the operation of this form of the invention it will be apparent that there is provided a pair of sticks 22 the outer ends of which are interconnected by means of a cord 23 which is preferably of that type known as a "chalk line string." The device may be placed upon the string by placing the portion 10 thereon and thereafter manipulating the sticks 22 so as to balance the toy upon the string 23 and at the same time to cause it to rotate. When sufficient rotation has been obtained it will be apparent that the blades 20 will cause air to flow through the openings in the disc 18, indicated at 24 and thence through the conical portions 11 of the body and finally through the openings 21 in such bodies thus producing between the openings 24 and the openings 14 a siren-like noise.

In Figures 4 and 5, there is illustrated an optional form of the invention wherein the reduced portion 10 has centrally and longitudinally mounted therein a whistle 30 and there is integrally formed adjacent the outer end of each of the cones 11 a spider 31 which, in turn, has integrally formed therewith a pair of propeller blades 32. The blades 32 are aligned with the

indentations in the scalloped outer edges 12 of the conical portions 11.

In the operation of this form of the invention, the device will be balanced and rotated in the manner above described with regard to the device shown in Figure 2 and it will be apparent that the propeller blades 32 will cause a passage of air through the device thereby actuating the whistle 30 to produce a weird and amusing sound.

While but two forms of the invention have been shown and described herein, it will be readily apparent to those skilled in the art that many minor modifications may be made without departing from the spirit of the invention or the scope of the appended claim.

What is claimed is:

A device of the character described comprising a body in the shape of a centrally balanced hollow double-conical frustum having its lesser diameter at the center thereof, scalloped outer edges for said body, and means operable by the rotation of said body for producing sound, said means comprising a whistle fixed longitudinally

5 in the portion of lesser diameter, and propeller blades mounted in the outer ends of each of the conical portions, said propeller blades being interconnected with said conical sections by spiders, and said conical sections, spiders and blades all being formed integrally for simultaneous rotation, the blades of said propeller being aligned with the indentations in the scalloped outer edges to permit lateral direction of air thereto, air passed into said frustum by said blades and through said whistle sounding said whistle.
